UNITED STATES PATENT OFFICE.

LINN B. ABBOTT, OF BRIDGEPORT, CONNECTICUT.

INSULATOR.

1,113,399.

Specification of Letters Patent.

Patented Oct. 13, 1914.

Application filed June 12, 1911. Serial No. 632,656.

To all whom it may concern:

Be it known that I, LINN B. ABBOTT, a citizen of the United States, residing at Bridgeport, in the county of Fairfield and the State of Connecticut, have invented a new and useful Insulator, of which the following is a specification.

My invention relates to improvements in insulators for use with pull switches, sockets or the like, in which a flexible metallic cord or chain is used as an actuating medium, and the objects of my improvement are, first, to provide means of guarding the operator against accidental shock by effectually insulating the operating chain from the other parts of the mechanism. Second, to provide insulation which can be inserted with great facility. Third, to provide an easy means of lengthening or joining a broken chain; which operation is extremely difficult to one not equipped for this work.

With these and other objects in view, which will be readily apparent to those skilled in the art, my invention consists of the novel construction, combination and arrangement of parts hereinafter more fully described, illustrated and claimed.

While susceptible to embodiment in various ways by the use of different mechanical equivalents, my invention is well exemplified by the single form thereof shown in the accompanying drawings, in which:

Figure I is an external view of an electrical pull socket embodying the present invention. Figs. II and III are longitudinal sections of my novel insulator. Fig. IV is a side view of a terminal before being embedded in the insulating material. Fig. V is a projection of Fig. IV showing the edge view of this terminal and Fig. VI is a projection of Fig. V showing the top view of the same.

Confining my description to the preferred form shown in the drawing, but without thereby limiting my invention, 1 is a pull socket for electric lights, of any ordinary construction, 2 is the operating chain composed of a series of metallic beads or balls, flexibly joined together, and such as is commonly used in connection with such socket. 3 is my novel insulator as inserted in said chain.

Referring to Figs. II and III, 4 is the body of my insulator composed of any insulating material. 5 and 5^a are spring ter-

minals made from any spring metal, and which are molded or similarly confined partly within the insulating material, and are spaced apart to prevent electrical conduction.

Referring to Figs. IV, V and VI, the spring terminals are made preferably from a single piece of metal folded back upon itself as at 6, in which position it tends to remain. They are provided with a hole 7 through the sides, which hole is adapted to encircle a ball of the chain. Another opening is formed in the end of the spring as 8, which opening allows space for the cord or link which connects the balls of the chain. This latter opening flares outwardly toward the end as at 9, which allows a ball of the chain to be inserted with ease and which in no way interferes with the retaining action of the spring after the ball is in place. These spring terminals are preferably partially molded into the insulating material which forms the body of the insulator and are somewhat enlarged toward the end as shown at 10 to insure their retention therein. To insert the insulator, a ball of the chain is pressed against the flaring end of the spring terminal. This separates the two parts of the spring and allows the ball to enter the opening 7, after which the spring returns to its former condition and holds the ball securely against retraction.

Having thus described my invention, what I claim as new is:

1. In an insulator for a conductor, the combination of two metal elements, the outer ends of each of said elements having yieldingly separable parts for engaging an end of the conductor between said parts, the inner ends of each of said elements being spaced apart from each other, and insulating material enveloping and embedding said inner ends for insulating from each other and mechanically securing said elements.

2. In an insulator for a conductor, the combination of two metal elements, the outer ends of each of said elements having two yieldingly separable spring blades for receiving and removably clamping between them an end of the conductor, the inner ends of each of said elements being spaced apart from each other, and insulating material enveloping and embedding said inner ends for insulating from each other and

mechanically securing said elements, the spring blades of said elements extending within said insulating material.

3. The combination with a conductor having spherically shaped ends, of an insulator comprising two metal elements, the outer ends of each of said elements being perforated, spring blades clamping between them a spherically shaped end of said conductor, the said spherically shaped end seating in said perforations, the inner ends of

each of said elements being spaced apart from each other, and insulating material enveloping and embedding said inner ends for insulating from each other and mechanically securing said elements. 15

In testimony whereof, I have hereunto set my hand this tenth day of June, 1911.

LINN B. ABBOTT.
